(57) **CLAIM**

The ornamental design for a humidifier, as shown and described.

DESCRIPTION

FIG. 1 is a top perspective view of a humidifier, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of area "FIG. 9" in FIG. 1;

FIG. 10 is an enlarged view of area "FIG. 10" in FIG. 2; and,

FIG. 11 is an enlarged view of area "FIG. 11" in FIG. 2. The broken lines in the drawings illustrate the portions of the Humidifier, which form no part of the claimed design.

The dot-dot-dash broken lines in the drawings depict the boundary of the enlarged views and form no part of the claimed design.

The humidifier may have the functionality of enhancing the air humidity and essentially diffusing oil aroma.
